UNITED STATES PATENT OFFICE

126,561

DESIGN FOR A LAWN STAND FOR SUPPORT- ING OR HOLDING MISCELLANEOUS AR- TICLES

Albert B. Tenney, Boston, Mass.

Application January 31, 1941, Serial No. 98,614

Term of patent 14 years

To all whom it may concern:

Be it known that I, Albert B. Tenney, a citizen of the United States of America, residing at Boston, in the county of Suffolk and Commonwealth of Massachusetts, have invented a new, original, and ornamental Design for a Lawn Stand for Supporting or Holding Miscellaneous Articles, of which the following is a specification, reference being had to the accompanying drawing, forming a part thereof.

Fig. 1 is a side elevational view of a lawn stand for supporting or holding miscellaneous articles embodying my new design; and

Fig. 2 is an enlarged top plan view of the top element of Fig. 1.

I claim:

The ornamental design for a lawn stand for supporting or holding miscellaneous articles, substantially as shown.

ALBERT B. TENNEY.
